UNITED STATES PATENT OFFICE.

JOHN BAPTISTE POYET, OF PHILADELPHIA, PENNSYLVANIA, ASSIGNOR TO
THE HENSEL, COLLADAY COMPANY, OF PENNSYLVANIA.

SKIRT-PROTECTOR.

SPECIFICATION forming part of Letters Patent No. 621,134, dated March 14, 1899.

Application filed October 20, 1898. Serial No. 694,075. (Specimens.)

To all whom it may concern:

Be it known that I, JOHN BAPTISTE POYET, a citizen of France, residing in the city and county of Philadelphia, State of Pennsylvania, have invented a new and useful Improvement 5 in Skirt-Protectors, which improvement is fully set forth in the following specification and accompanying drawings.

My invention is a skirt-protector consisting 10 of a fabric composed of a double head formed of warp and weft threads and a brush, one member of said head having a greater number of weft-threads than the other, whereby the protector is curved in the direction of its 15 length.

Figure 1 represents a face view of a piece 20 of skirt-protector embodying my invention. Fig. 2 represents a section thereof on line $x-x$, Fig. 1. Fig. 3 represents a face view of one 25 of the heads of the protector. Fig. 4 represents a face view of a piece of fabric as a blank from which the protector is made. Fig. 5 represents what may be termed a "section" 30 of the fabric in the process of manufacture, showing the course of the thread or yarn in forming the heads and brush of the article.

Similar letters and numerals of reference indicate corresponding parts in the figures.

Referring to the drawings, A designates a 35 piece of skirt-protector, the same consisting of the heads B and C, formed of two fabrics, and the brush D, said heads joining each other and the brush at the place E as an integral fabric.

The head C is woven loose in comparison 40 to the head B, or, in other words, the head B is more compact or dense than the head C, there being a greater number of wefts in the head B, so that one head draws against the other or is resisted by the other at the place E. Consequently a curve is imparted to the 45 protector in the direction of the length, the same thus being adapted to conform to the edge of the skirt to which the protector is secured.

The two heads B and C are employed for 50 sewing or otherwise securing the protector to the skirt, the edge of the latter being fitted between said heads, and one head is made

wider than the other in vertical direction, so that the edge of one head extends beyond the other for convenience of grasping the same or inserting the fingers between the two heads for readily separating the latter.

55

In the manufacture of a fabric for the protector I form two sets of heads and float the wefts or filling-threads from one set of heads to the other, after which the floated yarn or threads are cut at the center thereof, forming 60 two distinct protectors, each consisting of two heads and a brush, as will be apparent on reference to Fig. 4. As a method of manufacturing said fabric I employ the warp-threads 1 and 2, which are separated, as shown in Fig. 65 5. I also employ the warp-threads 3, 4, and 5 for a purpose to be hereinafter described, and I employ the filling thread or yarn 6, which is woven with the warp-threads 2 and the warp-threads 5 and 3 of the left head B, 70 and after leaving the latter threads it passes over the warp-threads 4 and then is crossed and floated to the right-hand head B, where it passes under the warp-thread 4 and is woven with the threads 3, 5, and 2 of said right-hand head B. When the thread has made its shot, it returns as number 7, being woven with the threads 2, 5, and 3 of said right-hand head B, and passes over the threads 4 of said right-hand head B. Then it floats across to 80 the left-hand head B under the thread 4 and is woven with the threads 3, 5, and 2 of said left-hand head B. The thread returns as number 8 and is shot across and woven similar to shot number 6 and is returned as number 9 from the right-hand head B; but after the thread 9 reaches the warp-thread 5 of the left-hand head B it is turned to the left-hand head C and woven with the warp-thread 1 of said head C, then returned to the threads 3, 90 4, and 5 of the left-hand head B and floated across to the right and woven with the warp-threads 3, 4, and 5 of the right-hand head B, and then turned to the right-hand head C and woven with the warp 1 thereof, it then 95 being returned to the right head B, woven with the threads 3, 4, and 5 thereof, crossed and floated to the left and woven with the warp-threads 3, 4, 5, and 2 of the left-hand head B, it then being back to the starting- 100

point, so that each pair of heads is distinctly formed and bound together by the threads 5 and 3, while the crossed and floated material constitutes a body which when cut through 5 centrally forms a brush for each two-part head. Furthermore, the threads 4 are left within the brushes and serve to spread the same and render them fluffy.

It will be seen that the heads B are of greater 10 density or compactness than the heads C, having a greater number of wefts in them and woven more tightly than said heads C, which are thus more open and loose fabrics than the heads B. Hence as the two heads are of different 15 degrees of density or compactness or are unequal in their nature and are united at or about a place adjacent to the brush one head draws on the other and so imparts a curve to the fabric, the effect of which is shown in 20 Fig. 1.

Having thus described my invention, what I claim as new, and desire to secure by Letters Patent, is—

1. A skirt-protector consisting of a fabric 25 composed of a double head and a brush, one head having a greater number of weft-threads

than the other whereby the protector is curved in the direction of its length.

2. A skirt-protector consisting of a double head, and a brush, one head having a greater 30 number of weft-threads than the other, and the two heads being of different widths.

3. A fabric for a skirt-protector formed of two set of heads, each set being composed of warp and weft threads, the weft-threads being floated from one set of heads to the other, one member of each set of heads having a greater number of weft-threads than the other 35 member of said set.

4. A fabric for a skirt-protector formed of 40 two sets of heads, each set being composed of warp and weft threads, the weft-threads being floated from one set of heads to the other, one member of each set of heads having a greater number of weft-threads than the other 45 member of said set, and the members of each set of heads being of different widths.

JOHN BAPTISTE POYET.
